UNITED STATES PATENT OFFICE.

WILSON A. STREETER, OF PHILADELPHIA, PENNSYLVANIA, ASSIGNOR TO THE BAILEY,
BANKS & BIDDLE COMPANY, OF PHILADELPHIA, PENNSYLVANIA, A CORPORATION
OF PENNSYLVANIA.

DESIGN FOR A FINGER-RING OR SIMILAR ARTICLE.

52,757.

Specification for Design.

Patented Dec. 10, 1918.

Application filed August 28, 1918. Serial No. 251,852. Term of patent 14 years.

To all whom it may concern:

Be it known that I, WILSON A. STREETER, a citizen of the United States, residing in the city and county of Philadelphia, State of Pennsylvania, have invented a new, original, and ornamental Design for Finger-Rings or Similar Articles, of which the following is a specification, reference being had to the accompanying drawing, forming part thereof.

Figures 1 and 2 are perspective views of opposite sides of a finger ring showing my new design.

Fig. 3 is a top view thereof.

I claim:

The ornamental design for a finger ring or similar article as shown.

WILSON A. STREETER.
